JAMES B. RUSSELL, OF WHEELING, WEST VIRGINIA.

Design No. 4,934, dated May 23, 1871.

DESIGN FOR LAMP-SHADES.

The Schedule referred to in these Letters Patent and making part of the same.

To all whom it may concern:

Be it known that I, JAMES B. RUSSELL, of Wheeling, in the county of Ohio and State of West Virginia, have invented and produced a new and original Design for Lamp-Shades; and I do hereby declare that the following is a full, clear, and exact description thereof, reference being had to the annexed drawing making part of this specification, in which the figure represents a perspective view of the shade.

This shade, which is termed the "urn shade," is made of glass or porcelain; and

The design consists in two distinct features—

First, in the novel formation of the main body of the shade; and

Secondly, in combining a scalloped upper end with this body.

In the annexed drawing—

A represents the neck of the shade, provided with the usual outwardly-turned lip for holding it to the burner.

The lower part B of the body of the shade gradually expands from its junction with the neck to the

line *b b*, it being slightly curved so as to present a convex outer surface.

An abrupt curve is made at the line *b b*, from which the upper elongated portion C of the body starts.

The outer surface of this part is made concave, with sides converging to a line, *c c*, from which they again diverge to the top.

The upper end of the shade terminates in an outwardly turned scalloped rim or crown, D.

What I claim as my invention, and desire to secure by Letters Patent, is—

The design for a lamp-shade, having an urn-shaped body, B C, and scalloped crown D, as shown and described.

In testimony whereof I have signed my name to this specification in the presence of two subscribing witnesses.

JAS. B. RUSSELL.
